UNITED STATES PATENT OFFICE.

CHAUNCEY N. DUTTON, OF PITTSBURG, PENNSYLVANIA, ASSIGNOR TO THE FUEL GAS AND MANUFACTURING COMPANY, OF SAME PLACE.

FLUID-METER.

SPECIFICATION forming part of Letters Patent No. 442,024, dated December 2, 1890.

Application filed August 4, 1888. Serial No. 282,014. (No model.)

To all whom it may concern:

Be it known that I, CHAUNCEY N. DUTTON, of Pittsburgh, in the county of Allegheny and State of Pennsylvania, have invented certain new and useful Improvements in Fluid-Meters, of which improvements the following is a specification.

My invention relates to fluid-meters of the class or type in which oscillating measuring cups or buckets are employed; and its object is to provide a simple and compact measuring mechanism which can be readily and accurately fitted and maintained in operative position and removed from the meter-casing whenever desired.

The improvements claimed are hereinafter fully set forth.

In the accompanying drawings, Figures 1 and 2 are vertical longitudinal sections through a fluid-meter embodying my invention at the lines x x and y y , respectively, of Fig. 4; Fig. 3, a plan or top view of the same, the upper casing-section and the measuring-receptacles on one side being removed; Fig. 4, a vertical transverse section at the line z z of Fig. 1; Fig. 5, a transverse section through the inlet-passages; and Figs. 6 and 7, bottom and top views, respectively, of the valve.

In the practice of my invention I provide a meter-case composed of an upper section 1 and a lower section 2, which are united so as to make tight joints by suitable lateral lugs or flanges and connecting-bolts. A central chamber 3^a is formed in the lower section 2, the walls 3 of said chamber extending to or near the top of the section. The volume of the chambers of the casing on each side of the central chamber 3^a is reduced as far as practicable by the provision of upwardly-projecting hollow bosses or displacers 4, the outer and inner walls of which are curved in substantial conformity with the curvature of the walls of the oscillating measuring cups or buckets to be presently described. The chambers around the displacers between the walls 3 of the central chamber 3^a and the outer walls of the casing are filled with a suitable sealing-fluid.

A tapered or conical sleeve or socket 6 is formed on one side of the lower casing-section 2, and a correspondingly-formed port-section

7 is fitted truly into said sleeve and secured to the section 2 around the same. A central inlet-nozzle 11, the outer end of which is adapted for connection to a pipe for the supply of the fluid to be measured, is formed in the port-section 7, around which nozzle the port-section is divided by longitudinal partitions, as shown in Fig. 5, into four passages 9. Each of said passages communicates by 60 a lateral port 8, formed in the walls of the port-section 7 and socket 6, with a tube 5 leading through one of the displacers 4 and terminating with an open end shortly above its top. The ports 8 of the tubes of each opposite pair 6; of displacers are located one above and the other below a horizontal plane passing through the axis of the socket 6 and port-section 7.

A horizontal transverse bearing-bar 18 is secured to and supported on the port-section 7 through the intermediation of a vertical post or standard 17, which is preferably, as shown, integral with the bar 18. Bearings 19, fixed to the top of the bar 18, support horizontal pivot-pins 20, upon which are journaled 75 two pairs of frames 21, each pair of which carries on opposite ends two measuring cups or buckets 22. The measuring-cups are closed at top and open at bottom, and are adapted to oscillate about the common axes of 80 the pivot-pins 20, the inner walls of each cup being curved in substantial conformity with those of one of the displacers 4, around which it fits freely and communicates at all points of its traverse with the tube 5, which passes 85 through the same. The fluid to be measured is admitted to and discharged from the measuring-cups in their upward and downward movements, respectively, by a rotary valve 12, controlling the passages 9 of the port-section 90 and the communicating ports 8 and tubes 5, said valve being coupled to and actuated by the movements of the measuring-cups, as presently to be described.

A valve-seat 10 is secured upon the inner 95 end of the port-section 7, said valve-seat being provided with ports corresponding in size and relative location with the open inner ends of the passages 9 and inlet-nozzle 11 of the port-section. A valve 12 is fitted truly on the seat 10, and is held thereto with a proper bearing by a spring 13, interposed between the valve

and a driving-yoke 14, which is secured upon a valve-shaft 16 and engages recesses on the back of the valve. The shaft 16 is journaled in a bearing in an arch-bar 15, secured to the inner end of the port-section 7. The two inner frames 21 of the measuring-cups are provided with arms 23, coupled by links 24 to a crank-pin 25, which is secured to a plate 26, fitted to slide in guides in a block 27, fixed to the end of the valve-shaft 16. A threaded stem is formed upon one end of the plate 26, its thread being engaged by an adjusting-nut 36, having a recess in its periphery, on which fits a projection on the plate 26, so as to prevent longitudinal movement of the nut while permitting its rotation, such rotation moving the plate 26 and attached crank-pin 25 longitudinally in the block 27, and increasing or diminishing the length of the valve-shaft 16, crank-arm accordingly as the adjusting-nut is turned in one or the other direction. It will be obvious that the range of traverse of the measuring-cups will be correspondingly increased or diminished, as may be desired.

25 A radial passage 28, covered by a shell 29, is formed in the valve 12, said passage leading from a central port in the valve, which port is constantly in communication with the inlet-nozzle, to a segmental port 30 near its periphery, and a corresponding port 31 extends through the valve diametrically opposite the port 30. The ports 30 and 31 are each adapted to communicate with the passages 9 of the port-section 7, the fluid to be measured being delivered from the inlet-nozzle 11 to the measuring-cups 22, through the passage 28, port 30, passages 9, ports 8, and tubes 5, and being discharged from the measuring-cups into the central chamber 3^a of the meter-casing, through the tubes 5, ports 8, passages 9, and port 31. The measured fluid is discharged from the meter through a pipe connected to a nozzle 32 on the upper casing-section 1. The ports 30 and 31 are each of such length as to effect the simultaneous admission of fluid to be measured into two adjacent passages 9 and its simultaneous discharge through two oppositely-disposed passages, and the opposite tubes 5, leading from the ports 8 to the measuring-cups, being, as before described, diametrically disposed respectively above and below the horizontal axial plane of the port-section, it will be seen that while fluid is being admitted to the 50 measuring-cup of each pair on one side of the axis of the pivots 20 it will be discharged from the opposite measuring-cup of each pair.

The frames 21, which carry the measuring-cups, are so connected to the crank-pin 25 that when one of the frames, as actuated by the charging of one of its measuring-cups, has reached such a position that the crank is on a dead-center—that is to say, when the center line of the link 24 coincides with a line drawn through the point of connection with the frame and the axis of the shaft 16 the link 24 of the other frame will beat such

an angle to the crank that the movement of said frame will continue the forward rotation of the crank-pin and the connected valve-shaft and valve.

The spaces around the displacers are connected by a pipe 33 with a pipe 34, leading out of the lower portion of the lower casing-section 2, in order to admit of the supply to said spaces of a proper sealing fluid to the desired level without removing the upper section 1 and for renewing the sealing fluid from time to time, as may be required. The registering mechanism B, which may be of any suitable construction and does not form part of my present invention, is driven by the engagement of the crank-pin 25 with a driving-arm 35, connected with the registering mechanism, as shown in Fig. 4.

It will be seen that the port-section 7, which is socketed in the meter-casing, forms the support of the entire measuring mechanism, the measuring-cups being journaled upon a bearing-bar connected to the port-section, and the valve controlling the supply and discharge of fluid to be measured working on a seat on the port-section and its shaft being journaled thereon. The measuring mechanism may consequently be accurately adjusted in proper operative relation and maintained therein; and may be readily removed for the purposes of renewal or repair whenever required.

I claim as my invention, and desire to secure by Letters Patent—

1. In a fluid-meter, the combination of an inclosing-case, a lateral socket thereon, a port-section secured in said socket and provided with a central inlet-nozzle and a series of passages and ports for the passage of fluid to be measured, a bearing-bar fixed upon and supported by the port-section, one or more pairs of measuring cups or buckets journaled to oscillate upon pivots on said bearing-bar, tubes leading from ports in the port-section and socket to the interior of the measuring-cups, and a rotary valve journaled on the port-section, said valve being coupled to and actuated by the measuring-cups and controlling the supply and discharge of fluid to and from the same through the port-section, substantially as set forth.

2. In a fluid-meter, the combination of an inclosing-case, a lateral socket thereon, a port-section secured in said socket and provided with a central inlet-nozzle and a series of lateral passages leading from ports on its inner end to lateral ports in the port-section and sockets, tubes leading upwardly from the lateral ports of the port-section and socket, the opposite tubes communicating, respectively, with a port above and a port below the horizontal central plane of the port-section and socket, a bearing-bar fixed upon and supported by the port-section, measuring-cups journaled to oscillate in pairs upon pivots on said bearing-bar, each above one of the tubes leading from the lateral ports, a rotary valve journaled on the port-section and controlling

the inner end ports thereof, and connections coupling said valve to the measuring-cups, substantially as set forth.

3. In a fluid-meter, the combination of an inclosing-case, a lateral socket thereon, a port-section secured in said socket and provided with ports and passages for the supply and discharge of fluid to be measured to and from measuring cups or buckets, a rotary valve journaled on the port-section and controlling ports therein, measuring cups or buckets jour-

naled to oscillate in pairs in the case, a crank-pin connected adjustably to the shaft of the rotary valve, and connections coupling said valve to the measuring-cups, substantially as set forth.

In testimony whereof I have hereunto set my hand.

CHAUNCEY N. DUTTON.
